UNITED STATES PATENT OFFICE.

AMOS L. FOREMAN, OF CHICAGO, ILLINOIS, ASSIGNOR TO MILK BOTTLE CRATE COMPANY, OF CHICAGO, ILLINOIS, A CORPORATION OF ILLINOIS.

BOX OR CRATE.

Application filed February 11, 1924. Serial No. 691,942.

This invention relates to boxes or crates and its object is to provide the corners thereof with reinforcing and strengthening means which will also reduce wear and prolong the 5 life of the box or crate.

Milk bottle crates and other crates are frequently provided with stacking irons on the top thereof at opposite corners to facilitate stacking a plurality of crates one upon 10 the other. These stacking irons cause material wear and damage to the crates and it is an object of my invention to provide means for protecting crates against wear or damage from stacking irons.

15 A further object of the invention is to reinforce and strengthen the corners of wooden boxes and crates by means which will provide a metal face on the inside of the two parts forming the corner, and which 20 will also leave the outside of the corner bare of metal.

The invention also has for its object to provide a reinforcing and strengthening means for the corners of boxes and crates 25 which is easily made, is simple in construction, and is easily and securely applied to the box or crate.

In the accompanying drawings illustrating the invention,

30 Fig. 1 is a perspective view showing parts of two crates, one provided with my reinforcing and strengthening means at the lower corner, and the other provided with a stacking iron at its upper corner.

35 Fig. 2 is a sectional view illustrating the invention and showing the position which the stacking iron of another crate would occupy with relation to the reinforcing and strengthening means, and

40 Fig. 3 is a perspective view of the reinforcing and strengthening device.

I have illustrated the invention on the corner of a crate 5 which has a shoe-piece 6 and a slot 7. The reinforcing and strengthening 45 device comprises an angular channel member shown in Fig. 3 and consisting of two parts, duplicates of each other, and comprising the connecting web 8 and the flanges 9, 10, each provided with holes 11 to receive 50 the nails 12. The two parts of the reinforcing and strengthening device are formed by two channels with their webs integrally connected, the said parts being arranged at an angle to each other to correspond with the 55 angularity of the corner in which they are

fastened. The ordinary crate has right angle corners, as indicated in the drawings, and for such corners the device will, of course, have its parts located at right angles to each other. This device may be conveniently stamped out of sheet metal and it is applied to the crate as indicated in Fig. 1, on the inside of the crate with the flanges of one part embracing the shoe-piece 6, and with the upper flange of the other part 60 seated in the slot 7. I prefer to recess the shoe-piece 6 at 12 and the other member of the corner at 13 to receive the lower flanges 9, 10, so that they will lie flush with the bottom of the box or crate. Nails are driven 65 through portions of the crate and through the flanges of the reinforcing and strengthening device and securely hold the device in its proper position with faces of the webs forming faces at the inside corner of the 70 crate.

The device is especially useful for protecting the crate against damage from stacking irons, like 14, for example, which are often provided on boxes and crates. It will 80 be noted that the projection 15 of the stacking iron will engage only metal faces of the reinforcing and strengthening device on the bottom of an adjacent box or crate. This entirely prevents that damaging wear which 85 results when the boxes or crates are not protected against the stacking irons.

My invention provides a simple but strong and substantial means for reinforcing and strengthening the corners of wooden boxes 90 and crates, and which can be easily and economically made and applied to the box or crate. Furthermore, the device is so constructed and applied that it will not form projections on any exposed surface of the 95 box or crate and, therefore, it does not interfere in any way with handling the box or crate.

I have shown the invention in a simple form which I have found adapted for the 100 purpose, but it is apparent that it may be changed in details of construction without departing from the invention or sacrificing its advantages, and I reserve the right to make all such changes as fairly fall within 105 the scope of the following claim.

I claim:—

The combination with a box or crate, of means for reinforcing and strengthening an exposed corner of the same, said means com- 110

prising an angularly bent channel member embodying a web and pairs of flanges applied to the inner walls of the box or crate at an exposed corner thereof, the web of said channel member providing a facing for the meeting inner walls of the box or crate at said corner and one flange of each pair be-

ing embedded in said walls and the other flanges bearing against the exposed edges of the box or crate at said corner, and fastenings projecting through said flanges and embedded in the box or crate. 10

AMOS L. FOREMAN.
